UNITED STATES PATENT OFFICE.

PHILIP A. WEIGEL, OF RIVERTON, NEW JERSEY.

PERMUTATION LOCK.

Application filed July 30, 1925. Serial No. 47,005.

My invention relates to improvements in a permutation lock and particularly relates to a lock which is operated by push bars in place of a key. The object of my invention is to provide a lock having tumbler blocks of novel construction adapted for operating the bolt-controlling member of the lock; a further object is to provide means for readily adjusting the position of the tumbler blocks, in relation to the bolt-controlling member, whereby the combination of the lock may be readily changed; a still further object is to provide a novel means for operating the bolt of the lock when the bolt-controlling member is released; a still further object is to provide means for releasing the tumbler blocks and returning the same to their normal positions; a still further object is to provide lock mechanism which is adapted to be arranged in either a cylindrical casing or a flat casing of the pad lock type; and a still further object is to provide various novel forms of construction and arrangement of the parts, which will be more fully hereinafter described and claimed.

Fig. 1 is a longitudinal sectional view as on line 1—1, Fig. 3, showing a cylindrical lock embodying my invention; Fig. 2 is an end elevation of Fig. 1; Fig. 3 is a transverse section on line 3—3, Fig. 1; Fig. 4 is a longitudinal sectional view on line 4—4, Fig. 1; Fig. 5 is a longitudinal sectional view on line 5—5, Fig. 1; Fig. 6 is a partial longitudinal sectional view on line 6—6, Fig. 1; Fig. 7 is a transverse sectional view on line 7—7, Fig. 1; Fig. 8 is a sectional view showing my improved lock mechanism arranged in the form of a pad lock; Fig. 9 is a vertical sectional view on line 9—9, Fig. 8; Fig. 10 is a partial vertical section on line 10—10, Fig. 8; Fig. 11 is a partial transverse vertical section on line 11—11, Fig. 8; and Fig. 12 is a view similar to Fig. 11, as on line 12—12, Fig. 8.

In the accompanying drawings in which like reference characters refer to like parts, 10 represents the outer casing of the lock having a flange 12, adapted for securing the casing 10 to the inner face of a door, not shown in the drawing. At the opposite end of the casing 10 is provided a head 13, which forms the outer end of the lock and intended to be exposed upon the outer surface of a door. The head 13 is provided

with apertures 14, which are occupied by 55 the push buttons or heads 16 of the push bars 17, 18, 19, 20, 21 and 22, adapted for operating the lock.

Within the casing 10 is an inner casing 25 having a head 26 with an annular flange 60 27, adapted to be detachably secured to the flange 12, so that the inner casing and the lock mechanism may be readily withdrawn from the casing 10, without removing the latter from the door for the purpose of 65 changing the combination of the lock when desired.

The inner casing 25 is provided with an annular bearing 30, secured therein, to which bearing 30 is secured a disk 31 forming a 70 bearing. The casing 25 is also provided with a disk 32 secured in said casing, forming a bearing; and a longitudinal bearing 35 is secured between the bearings 30 and 32. Said bearings form supports or guides for 75 the mechanism forming the lock, more fully hereinafter described.

The push bars 17, 18, 19 and 20 are adapted for operating the tumbler blocks and are all of similar construction, therefore the 80 following description of one, will apply to the duplications of the parts. A plurality of push bars is provided for the purpose of providing different combinations controlling the lock mechanism.

The push bar 19 is shown in Fig. 1, is 85 slidably mounted in the bearings 30 and 31 and has a portion which is of rectangular cross-section to prevent its rotation in said bearings. The push bar 19 carries a push 90 button 16 at one end which projects through the head 13 at one end of the casing 10 and adapted to be operated with the fingers by pushing the button 16 against the action of a spring 37, into the operative position, and 95 when released the spring 37 will return the bar 19 to its normal position, which position is controlled by a stop 38 on the bar 19.

The push bar 19 is provided with a pawl 39, pivoted upon a shaft 40, secured in the 100 bar 19, and held in operative position by a spring 41 secured on said bar 19. The pawl 39 engages a tumbler block 42 mounted upon a body bar 43, which latter is slidably mounted in the bearings 31 and 32. The 105 body bar 43 is moved by a spring 44, into a normal position with the one end of the bar 43 against the head 13 of the casing,

which latter acts as a stop to limit the movement in one direction. The body bar 43 has a circular portion 45 surrounded by the spring 44, and a flat portion which forms a shoulder 47 against which the spring 44 acts. The flat portion of the bar 43 prevents the bar from rotating in the bearing 31.

The tumbler block 42 is adjustably mounted upon the bar 43 and said block 42 is provided with teeth 48 adapted to be engaged by the pawl 40 adapted for moving the block 42 and the body bar 43 longitudinally. The block 42 is also provided with a longitudinal rib 49, having a transverse recess 50 formed therein, adapted to cooperate with a bolt-controlling-member 52.

A bolt-controlling-member 52 is secured upon a longitudinal shaft 53 positioned centrally of the casing 10. Said shaft 53 is rotatably mounted in the bearing 32 at one end thereof, and the other end is supported upon the portion 55 of the central push rod 21, which latter is allowed to move longitudinally in relation to the shaft 53, as said portion 55 is adapted to freely enter the recess 56 formed in a shaft 53. The bolt-controlling-member 52 is in the form of a disk having slots 57 formed in its periphery in parallel relation with the axis of the shaft 53. The rib 49 on the block 42 is adapted to occupy the slot 57 in the disk 52 and hold the disk and shaft 53 against rotation. When the block 42 is moved by the push bar 19 until the transverse recess 50 formed through the rib 49 of the block is in register with the disk 52, the disk will be free to rotate, thus releasing the bolt-controlling-member 52 and permitting the bolt 64 to be operated as hereinafter described.

Secured to the shaft 53 is a hub 60, extending from which are lever arms 61 and 62. Said arm 61 engages a pin 63 secured to the bolt, or latch, 64, slidably mounted in the walls of the casings 10 and 25, and adapted to engage any suitable form of locking member, not shown in the drawings in a manner well known in the art. The lever 61 is provided with an enlarged portion 65, having an opening formed therein, which opening permits the end 45 of the body bar 43 to move through said recess without interfering with the action of the lever 61. The lever arm 62 projects from the hub 60, in the opposite direction from the arm 61 and engages a bifurcated arm 66, forming part of a pivot plate 67, pivotally mounted upon a pin 68, secured in the longitudinal bearing 35, thus said pivot plate 67 swings upon the pin 68 along with the movements of the bolt 64 and the shaft 53, carrying the bolt-controlling-member 52, which parts move simultaneously. The bolt 64, along with the pivot plate 67 and other parts associated therewith, are moved into the

extreme positions in either direction by a spring 70, secured at one end upon a pin 71, mounted in the bearing 32 and its opposite end is secured upon a pin 73, mounted upon the lever arm 61. Said pin 73 being so located upon the lever 61, in relation to the fixed pin 71 that the spring 70 will tend to move the lever 61 away from the dead center line formed by the pins 71 and 73 and the shaft 53 on which the lever 61 is pivoted. When the bolt 64 and the lever arms 61 and 62 are in the position shown in full lines, Fig. 3, the pivot plate 67 will be in the position shown in full lines in Fig. 4.

Upon the pivot plate 67 are fingers 75 and 76, located at the opposite side of the pivot pin 68 from the arm 66 which engage the arm 62. When the lever arm 62 is in either extreme position, one of the fingers 75 or 76 will be located adjacent to the center line extending through the pivot pin 68, and the push bar 22, as shown in full and dotted lines in Fig. 4.

The push bar 22 is provided with a sliding plate 78, which is secured to the end portion 23 of the push bar 22. Said plate 78 is slidably mounted upon the bearing 35 by means of screws 79; pivotally mounted upon a pin 80, secured in the sliding plate 78, is a toggle-plate 81, having recesses 82 and 83 formed in the free end thereof. A pointed projection 84 upon the toggle-plate 81 forms a double faced cam adapted to engage one of the fingers 75 and 76 when the push bar 22 is pushed inwardly. As the push bar 22 is moved inwardly the toggle-plate 81 engages a finger 75 or 76 and moves the pivot plate 67 about the pivot 68 and the toggle-plate 81 also moves about the pivot 80. A slight movement, thus imparted to the pivot plate 67, will move the lever arms 61 and 62 and the shaft 53 until the spring 70 has passed the dead center line of the shaft 53 when the tension of said spring 70 will continue to move the parts into the opposite position, thus shifting the bolt 64. When the pressure of the fingers is removed from the push bar 22, the spring 70 will force the push bar outwardly into its normal position. The toggle-plate 81 will be returned to its central position, as shown in Fig. 4, by the action of the springs 86 and 87, carried by a curved rod 88 having its ends secured in wing plates 89 and 90 forming part of the sliding plate 78. The toggle-plate 81 has a boss 91 secured centrally thereon. Said boss is provided with an aperture through which the rod 88 freely passes. When the toggle-plate 81 is swung in either direction from the center line of the push bar 22, the boss 91 will engage either of the springs 86 or 87, placing the same under sufficient tension so that when the push bar 22 is again released, the

springs 86 or 87 will tend to swing the toggle-plate 81 to its central position as shown in Fig. 4. It will thus be seen that, when the tumbler block 42 is moved so as to bring the recess 50 in said block 42, into register with the bolt-controlling-member 52, the latter and the shaft 53 will thus be released, and the bolt 64 may be shifted by pressing the finger against the button 16, 10 carried by the push bar 22.

The tumbler block 42 is adapted to be moved by the pawl 39 when the push bar 19 is moved inwardly by pressure upon the button 16 on the bar 19. A latch pawl 92 is pivotally mounted upon a projecting lug 93 formed on the bearing 30. Said latch pawl 92 is adapted to be moved into engagement with the teeth 48 of the block 42 by the action of a spring 94. Said pawl 92 automatically engages the teeth of the block 42, as it is advanced by the pawl 39, and prevents the spring 44 from moving the body bar 43 and the block 42 towards its normal position when the pawl 39 is released from engagement with the teeth 48 of the block 42. Thus it will be seen that the block 42 and the body bar 43 may be advanced intermittently by pushing the push bar 19 by finger pressure on the button 16, secured to said bar 19.

The tumbler block 42 and body bar 43 may be released from engagement with the pawls 39 and 92 and allowed to return to its normal position through the action of the spring 44, by means of releasing mechanism, consisting of the push bar 21, slidably mounted in the bearing 31 and telescoping at its other end with the shaft 53, as above described. Upon the push bar 21 is secured a hub 96 of a drum, consisting of spokes 97 and a rim 98. The spokes 97 of the drum are arranged to pass freely between the push bars as shown in Fig. 7 and thus support the rim 98 of the drum in alignment with the pawls 39 and 92. The pawl 92 operates through the aperture 99 formed in the rim 98 of the drum so that said pawl 92 may project through the drum and engage the teeth 48 of the tumbler block. 50 When the finger is pressed against the button 16, secured to the push bar 21, the drum is moved so that the rim 98 engages the pawls 39 and 92 simultaneously and, lifts said pawls out of engagement with the teeth 48 of the block 42, thus allowing the spring 44 to move the body bar 43 and the block 42 back to the original position, as shown in Fig. 1. When the push bar 21 is again released the spring 100 will return the push bar 21 to its normal position moving the rim 98 of the drum out of engagement with the pawls 39 and 92, allowing them to engage the teeth of the block 42.

To permit the combination of the lock 65 to be changed, the tumbler block 42 is ad-

justably mounted upon the body bar 43, on which it is slidably longitudinally by means of a screw 102, (see Fig. 6) which is mounted upon a lug 103 formed upon the side of the body bar 43, in which lug 103, 70 the screw 102 is free to turn. The screw 102 is threaded into a lug 104 formed upon one side of the tumbler block 42. When it is desired to change the combination of the lock the inner casing 25 is removed from the outer casing 10. The entire mechanism of the lock is mounted within the inner casing 25, so that it may readily be withdrawn from the casing 10. When so withdrawn, the adjusting screws 102 are accessible 80 through holes 105 formed in the bearing 31, as shown in Fig. 6. By rotating the screw 102, the block 42 may be moved upon the body bar 43 into different positions, so that the block 42 will have to be moved 85 different distances by the pawl 39, to be put into a position to allow the transverse recess 50, of the block 42 to register with the bolt-controlling-member 52 and allow the latter to rotate and thus release the bolt 64. Each movement of the push bar 19 by a pressure of the finger upon the button 16, secured to said bar, will cause the pawl 39 to move the block 42, one tooth. 90

By adjusting the set screw 102 to a position which will bring the recess 50 into register with the disk 52, when the block 42 has been moved, one tooth, it will be seen that one pushing movement of the bar 19 will bring the block 42 into a position to release the disk 52, or the adjusting screw 102 may be set so that two, three or more teeth will have to be engaged by the pawl 39, upon successive movements of the bar 19 to bring the block 42 into a position to release the disk 52. As shown in Fig. 1 an extra tooth 42^a is provided upon the block 42 so that if the push bar 19 is pushed too many times the recess 52 will pass beyond the position necessary to bring it into register with the disk 52, so that the rib 49 will again lock the disk 52, and prevent the lock from being released. By having two or more push bars and tumbler blocks, such as shown in Fig. 7, in which four push bars 17, 18, 19 and 20 are shown, which are all similar to the push bar 19, and having similar operating mechanism as above described, various combinations may be obtained by adjusting the different tumbler blocks to different positions upon the body bars, so that a different movement, or different combinations, will be required for moving each of the different push bars before the bolt-controlling-member 52 will be free to rotate 105 through the recesses 50 formed in the several tumbler blocks.

The operation of my invention is as follows: The different tumbler blocks are first set by the adjusting screws 102, so that a 110

different number of movements will be required by the different push bars to bring the parts into a position to release the lock. The inner casing is then secured in the outer casing with the push buttons 16 projecting and exposed beyond the head 13 of the outer casing 10. By pushing the push button 16, to move the push bar 21 inwardly the rim 98 of the drum will release the pawls 39 and 92 from the several tumbler blocks 42, thus allowing the tumbler blocks and the body bars to return to their normal position by the action of the springs 44, thus locking the bolt-controlling-member 52, by the tumbler blocks, so that the member 52 can not rotate and the bolt 64 will be held in either the locked or unlocked position. To release the lock the push bars 17, 18, 19 and 20 are each pushed the required number of times, according to the combination into which the tumbler blocks are set. These successive movements will bring all of the tumbler blocks into a position so that the recess 50 will register with the bolt-controlling-member 52, which latter is thus released and free to be rotated. The push bar 22 is now moved inwardly by pressing upon the button 16, secured to said bar 22, which movement slides the sliding plate 78 and the toggle-plate 81 inwardly so that the latter will press against a finger 75 or 76, on the pivot plate 67, and turn the pivot plate 67 about the pivot pin 68 sufficiently to allow the spring 70 to slide the bolt 64 into the opposite position. Each movement of the bolt 64 will swing the pivot plate 67 into a position so that either the finger 75 or the finger 76 will be in a position ready to be engaged by the toggle-plate 81, and successive pushing movements upon the push bar 22 will shift the bolt 64 into opposite positions. To again lock the parts so that the bolt 64 can not be moved, it is only necessary to press the button 16, secured on the push bar 21, so that the rim 98 of the drum will release all the pawls 39 and 92 and allow the tumbler blocks 42 to return to their normal positions and thus lock the bolt-controlling-member 52 and the bolt 64 against further movement.

In the present embodiment of my invention, I have shown the improved lock mechanism arranged in a cylindrical barrel or casing, whereas the mechanism may be arranged in a casing of rectangular cross-section or in flat formation adapting the same for a pad lock as illustrated in Figs. 8 to 12, which changes may be readily made without departing from the scope of my invention.

The embodiment of my invention disclosed in Figs. 8 to 12, comprises telescoping casings 110 and 112 of flat rectangular formation, in which the push bars 115, the latch operating bar 116 and the releasing bar 117 are arranged in the same plane, or approx-

imately the same plane, and adapted to be operated by finger pressure upon the buttons secured upon said bars which project through apertures formed in the end plate 113 of the outer casing 110.

The bolt-controlling-member 125 is slidably mounted in bearings 126 formed upon the inner casing 112. Said member 125 has transverse recesses 127 formed therein through which tumbler blocks 130 are movable by the push bars 115. Each block 130 is provided with a recess 131 which may be brought into register with the bolt-controlling-member 125, thus releasing the latter from locking engagement with the tumbler blocks 130.

There is a tumbler block 130 associated with each of the push bars 115, which are duplicates, thus only one is shown in Fig. 8 of the drawing. The push bar 115 has a pawl 133 pivotally mounted thereon, adapted for engaging with ratchet teeth 132 formed upon the tumbler block 130. By pressing the button and moving the push bar 115 inwardly against the spring 135, the pawl 133 will move the tumbler block 130 in relation to the bolt-controlling-member 125 into a position to release the latter, providing the bar 115 is moved the proper number of times according to the combination at which the lock is set. A latch pawl 137 is pivoted upon a bearing 134 formed on the casing 112, and prevents the return movement of the tumbler block 130, when the tumbler block is moved by the pawl 133.

The tumbler block 130 is movably mounted upon a body bar 138 and may be adjusted into different positions upon the body bar by means of a set screw 140, movable with the body bar. By means of said set screw the tumbler block may be set in different positions upon the respective body bar so as to change the combination formed by the several different tumbler blocks of the lock, in the manner above described. The body bar 138 is slideable longitudinally in bearings 141 and 142 formed upon the casing 112 and is movable to a normal position by means of a spring 143 positioned between the bearing 141 and a pin 144 upon said body bar.

When all of the tumbler blocks have been moved, by the push bars 115 into a position to release the bolt-controlling-member 125 the latter may be moved longitudinally in the bearings 126 by means of the latch operating bar 116, which is also movable by finger pressure upon a button upon the bar 116. Upon the inner end of the bar 116 is pivoted a link 146 which in turn is pivotally connected to a latch operating lever 147, which in turn is pivoted upon a pin 148 secured in the casing 112. The latch operating lever 147 is provided with a slot 149, which is occupied by a pin 150 secured in

the bolt-controlling-member 125, so that when the lever 147 is operated by the push bar 116 and rotated about the pin 148, the bolt-controlling-member 125 will be moved longitudinally in the bearings 126 by means of the pin 150, being engaged and acted upon by the lever 147. The free end of the lever 147 engages a pin 152 upon the latch bolt 153 and is adapted to move said bolt out of engagement with the shackle 155, which is pivotally mounted upon a pin 156 secured in the casing 112.

When it is desired to move the parts into locking position, the release bar 117 may be moved inwardly by finger pressure upon the button upon said bar 117, so that a cross-bar 158 secured upon the inner end of the push bar 117, will be moved under all of the pawls 133 and 137 and lift said pawls out of engagement with the teeth 132 of the tumbler blocks 130, thus permitting the springs 143 to return the tumbler blocks 130 and body bars 138 to their normal positions, in which the tumbler blocks will again enter the recesses 127 formed in the bolt-controlling member 125 and prevent the latter from sliding longitudinally. Unless said member 125 is released from engagement with the tumbler blocks and free to move longitudinally, the pin 150 thereon, will prevent the latch controlling lever 147 from moving about the pivoted pin 148, thus the operating bar 116 will be automatically locked.

All the parts of the lock mechanism are carried upon the inner casing 112, which may be withdrawn from the outer casing 110 by removing a screw 160, which extends through the opposite walls of both casings, as shown in Fig. 9. The screw 160 is provided with a flat surface 161 against which the latch controlling lever 147 is held and prevents said screw from rotating when the lock mechanism is in the locked position, therefore it is necessary to shift the lock mechanism into the unlocked position before said screw 160 can be rotated and removed from the casings. When the casings are separated the heads of the adjusting screws 140 are accessible through the open end of the inner casing 112, thus permitting said screws to be turned for setting the tumbler blocks into different positions upon the body bars and thus change the combination of the lock.

55 I claim:

1. A permutation lock comprising a casing, bearings secured in said casing, a block slidably mounted in said bearings, said block having a transverse recess formed therein, a bolt-controlling-member adapted to be held against movement by said block, said block having ratchet teeth formed therein, a pawl adapted to engage said teeth, a manually operated push bar upon which said pawl is mounted, said push bar being

slidably mounted upon said bearings and moveable parallel with said block adapted to move said block intermittently to bring said recess in alignment with the bolt-controlling-member to release the latter when 70 in alignment with said recess, a spring tending to move said block into a normal position, and a stop associated with said block adapted for varying the normal position of said block and thereby varying the required 75 movement of said block by said pawl to bring said notch into alignment with the bolt-controlling-member.

2. A permutation lock comprising a casing, bearings in said casing, a body bar slidably mounted in said bearings, a block slidably mounted upon said body bar, a bolt-controlling-member adapted to be locked against movement by said block when the latter is in certain positions, adjusting means operatively positioned between said body bar and said block adapted for setting the block at different positions upon the body bar for varying the movement of the block necessary to release the bolt-controlling-member and 80 means for moving said block in relation to the bolt-controlling-member.

3. A permutation lock comprising a casing, bearings in said casing, a body bar slidably mounted in said bearings, a block slidably mounted upon said body bar, a bolt-controlling-member adapted to be locked against movement by said block when the latter is in certain positions, an adjusting screw operatively mounted between said body 100 bar and said block adapted for setting the block at different positions upon the body bar for varying the movement of the block necessary to release the bolt-controlling-member from the block, and means for moving said block and the body bar in relation to the bolt-controlling-member.

4. A permutation lock comprising a casing, bearings in said casing, a body bar slidably mounted in said bearings, a block 110 slidably mounted upon said body bar, a bolt-controlling-member adapted to be locked against movement by said block when the latter is in certain positions, an adjusting screw operatively mounted in said block, a 115 lug upon the body bar in which the screw is rotatably mounted and secured against longitudinal movement upon said bar adapted for setting the block at different positions upon the body bar for varying the movement of the block necessary to release the bolt-controlling-member from the block, and means for moving said block and the body bar in relation to the bolt-controlling-member.

5. A permutation lock comprising a casing, bearings in said casing, a body bar slidably mounted in said bearings, a stop located in the casing adapted to hold the body bar in a normal position, a spring tending 130

- to move the body bar into said normal position, a block slidably mounted upon the body bar, a bolt-controlling-member adapted to be locked against movement by said block when the latter is in certain positions, an adjusting screw operatively mounted between said body bar and said block, adapted for setting the block at different positions upon the body bar for varying the movement of the block necessary to release the bolt-controlling-member from the block, and means for moving said block and the body bar in relation to the bolt-controlling-member.
6. A permutation lock comprising a casing, bearings in said casing, a body bar slidably mounted in said bearings, a block slidably mounted upon said body bar, means for adjusting said block in various positions upon said bar, said block having a transverse recess formed therein, a bolt-controlling-member mounted in said bearings adapted to be held against movement by said block, ratchet teeth formed upon said block, a pawl adapted to engage said teeth, a push bar upon which the pawl is mounted, said push bar adapted to be manually operated for moving said body bar and said block into a position with said recess in alignment with the bolt-controlling-member to release the latter, and springs adapted for returning said push bar and said body bar to a normal position.
7. A permutation lock comprising a casing, bearings in said casing, a block slidably mounted in said bearings, a spring adapted for moving said block to a normal position, a push bar adapted for moving said block against the action of said spring, a bolt-controlling-member adapted to be held against movement by said block when the latter is in certain positions and released from said block when the latter is moved by said push bar to a given position, a bolt slidably mounted in the casing, a push bar adapted for sliding said bolt when the bolt-controlling-member is released from said block, and springs adapted for returning said push bars to their normal positions.
8. A permutation lock comprising a casing, bearings in said casing, a block slidably mounted in said bearings, a spring adapted for moving said block to a normal position, a push bar adapted for moving said block against the action of said spring, a bolt-controlling-member adapted to be held against movement by said block when the latter is in certain positions and released from said block when the latter is moved by said push bar to a given position, a bolt slidably mounted in the casing, a push bar adapted for imparting an initial movement to said bolt when the bolt-controlling-member is released from said block, and a spring adapted for moving said bolt into the extreme position in either direction after said bolt is moved by said last mentioned push bar.
9. A permutation lock comprising a casing, bearings in said casing, a block slidably mounted in said bearings, a spring adapted for moving said block to a normal position, a push bar adapted for moving said block against the action of said spring, a bolt-controlling-member adapted to be held against movement by said block when in certain positions and released from said block when the latter is moved by said push bar to a given position, a shaft upon which said member is mounted, a bolt slidably mounted in the casing, a lever secured upon said shaft, an arm upon the lever operatively connected with said bolt, a second arm upon said lever, a pivot plate operatively associated with said second arm, and a second push bar slidably mounted in said casing adapted to engage said pivot plate for moving the bolt and the bolt controlling member when the latter is released from said bolt.
10. A permutation lock comprising a casing, bearings in said casing, a block slidably mounted in said bearings, a bolt-controlling-member adapted to be held against movement by said block when the latter is in certain positions, a manually operated push bar slidably mounted within the casing, a pawl upon said push bar adapted for moving said block, a second push bar mounted within the casing having means thereon adapted for disengaging said pawl from said block, a bolt slidably mounted in the casing, mechanism operatively positioned between said bolt and said bolt-controlling-member adapted for locking the bolt when said member is engaged by said block, and a push bar mounted within the casing operatively associated with said mechanism, adapted for shifting the bolt and said member when the latter is released from said block.
11. A permutation lock comprising a casing, bearings in said casing, a body bar slidably mounted in said bearings, a block adjustably mounted upon the body bar, a bolt-controlling-member adapted to be held against movement by said block when the latter is in certain positions, a push bar slidably mounted in said casing adapted for moving said block into a position to release the bolt-controlling-member, a bolt slidably mounted within the casing, mechanism operatively engaging said bolt and said member whereby the same are moved in unison, a push bar mounted within the casing adapted for shifting the position of said bolt when the bolt-controlling-member is released from said block, a push bar mounted within the casing, and releasing means controlled by said last mentioned push bar.

- adapted to disengage the first mentioned push bar from said block and means for returning said block to its normal position and engage said bolt-controlling-member.
- 5 12. A permutation lock comprising a casing, bearings in said casing, a body bar slidably mounted upon said bearings, a block adjustably mounted in said body bar, a spring adapted for moving said bar into a 10 normal position, a bolt-controlling-member adapted to be held against movement by said block when the latter is in certain positions, a push bar slidably mounted within the casing, a pawl upon said push bar adapted for 15 moving said block and said bar against the action of the spring, a second push bar mounted within the casing having means thereon adapted for disengaging said pawl from said block, a bolt slidably mounted in 20 the casing, mechanism between said bolt and said bolt-controlling-member adapted for locking the bolt when said member is engaged by said block, and a push bar mounted within the casing operatively associated with 25 said mechanism adapted for shifting the bolt and said member when the latter is released from said block.
13. A permutation lock comprising a casing, a block slidably mounted in said casing, a bolt-controlling-member adapted to be 30 held against movement by said block, said block having a transverse recess formed therethrough, adapted to be occupied by said member, a spring tending to move said block 35 into a normal position with said recess out of alignment with the bolt-controlling-member, said block having ratchet teeth formed therein, a manually operated push bar mounted in said casing, a pawl mounted upon 40 said push bar adapted to move said block tooth by tooth against the action of said spring, a latch pawl mounted upon said casing adapted to engage said teeth and hold the block against the action of said spring 45 whereby said block may be advanced by the first mentioned pawl to bring said recess into alignment with the bolt-controlling-member and release the latter, a manually operated push bar mounted in said casing, a pawl releasing device secured upon said last mentioned bar adapted to simultaneously disengage said pawls from said block and allow the spring to move the block to its normal 50 position and engage said bolt-controlling-member.
14. A permutation lock comprising a casing, a block slidably mounted in said casing and having a transverse recess formed therein, a shaft rotatably mounted in said casing, a lock-controlling-member secured upon said 55 shaft adapted to be held against rotation by said block, a manually operated push bar adapted for moving said block to bring said recess into alignment with said bolt-controlling-member and release the same, an arm secured upon said shaft, a pivot plate mounted within the casing, said pivot plate having one member thereof in operative engagement with the free end of said arm, a spring tending to rotate said shaft and move said arm and said lever into extreme opposite positions, a manually operated push bar positioned in alignment with the pivot point of said lever, said lever having a pair of fingers located at the opposite side of the 60 pivot point of the lever from the portion of the latter which engages said arm, said fingers upon said lever adapted to be positioned nearly in axial alignment with said last mentioned push bar, a member mounted upon and movable with said last mentioned push bar adapted to engage one of said fingers when in a position adjacent to the axial alignment of said last mentioned push bar whereby a longitudinal movement of the 65 latter will shift said lever and rotate the shaft carrying the bolt-controlling-member.
15. A permutation lock comprising a casing, bearings in said casing, a body bar slidably mounted in said casing, a spring tending to move said bar into a normal position, a block adjustably mounted upon said bar, ratchet teeth formed upon said block, a manually operated push bar mounted in said casing, a pawl pivoted upon said push bar 70 adapted to engage the teeth of said block and move the latter against said spring, a latch pawl mounted in one of said casings adapted to engage the teeth of said block and hold the latter against the action of said 75 spring, a bolt-controlling-member adapted to be held against movement by said block when in certain positions and released when said block is advanced by the said first mentioned pawl, a pawl releasing device adapted 80 for simultaneously disengaging said pawls from said block, a push bar slidably mounted within the casing adapted for operating said releasing device, a bolt operatively associated with the bolt-controlling-member 85 and means for shifting said bolt when said member is released from said block.
16. A permutation lock comprising a casing, a plurality of body bars slidably mounted in said casing, springs tending to move said body bars to a normal position, a tumbler block slidably mounted upon each body bar, an adjusting screw operatively positioned between the body bar and the block thereon adapted for setting the block 90 in different positions upon the body bar, push bars mounted within the casing adapted for advancing said blocks independently of each other, said blocks each having transverse recesses formed therein, a shaft 95 mounted in the casing concentrically in relation to said blocks, a disk secured upon said shaft, slots formed in said disk adapted to be occupied by said blocks and lock said disk against rotation when said blocks are 100

8
 in a position in which the transverse recesses of one of said blocks is out of register with the disk, a bolt mounted in said casing, a lever secured upon said shaft adapted for 5 operating said bolt, a second lever upon said shaft, a pivot plate operatively associated with said last mentioned lever, a push bar mounted within the casing adapted to engage said pivot plate and rotate said shaft, 10 a drum concentrically mounted in relation to the tumbler blocks, a push bar adapted for moving the drum to disengage said pawls from the blocks and a spring upon each push bar adapted to return the same to 15 a normal position.

17. A permutation lock comprising a casing, a head formed in one end of said casing, an inner casing adapted to be positioned within the first mentioned casing, bearings 20 in the inner casing, push bars slidably mounted in said bearings, said push bars having push buttons formed thereon, said head in the first mentioned casing having apertures formed therein adapted to be occupied by said push buttons, body bars 25 slidably mounted in said bearings, tumbler blocks mounted upon the body bars, adjusting screws operatively positioned between the body bars and said blocks adapted 30 for changing the position of said blocks upon the body bars, said adjusting screws being accessible for adjusting the same when the inner casing is removed from the outer casing, and a bolt-controlling-member adapted 35 to be controlled by the tumbler blocks.

18. A permutation lock comprising a circular casing, a head formed in one end of said casing, an inner casing adapted to be positioned within the first mentioned casing, 40 bearings in the inner casing, push bars slidably mounted in said bearings, said push bars having push buttons formed thereon, said head in the first mentioned casing having apertures formed therein through which 45 said push buttons may be operated, body bars slidably mounted in said bearings, tum-

bler blocks mounted upon the body bars, springs tending to force the latter into a normal position, a pawl upon each push bar adapted for moving said block; a latch pawl 50 adapted to hold the block against the action of said spring, adjusting screws operatively positioned between the body bars and said blocks adapted for changing the position of said blocks upon the body bar, said adjusting screws being positioned parallel with the body bars and accessible for adjusting the same when the inner casing is removed from the outer casing, a shaft rotatably mounted concentrically of the casing, a bolt-controlling-member secured upon said shaft 55 adapted to be controlled by the tumbler blocks, a bolt operatively connected with said shaft, a push bar adapted for rotating said shaft for moving said bolt when the tumbler blocks are in a position to release the bolt-controlling-member, a drum embracing said blocks, said drum having an aperture formed therein through which the latch pawls extend into engagement with 60 said block, and a push bar adapted for moving the drum axially for releasing said pawls from said blocks.

19. A permutation lock comprising, a casing, a plurality of tumbler blocks, bearings 75 located in the casing in which said blocks are slidable in a rectilinear direction, a bolt-controlling-member adapted to be held against movement by said blocks when the latter are in certain positions, push bars 80 mounted within the casing adapted for sliding said blocks into a position to release said member, a push button upon each push bar extending through the casing and accessible from without the casing, springs 85 adapted for moving said blocks and said push bars into normal positions, and adjusting means adapted for changing the normal position of said blocks relative to the bolt-controlling-member. 90

In testimony whereof I affix my signature.
 PHILIP A. WEIGEL.
